United States Patent Office

Des. 230,391
Patented Feb. 19, 1974

230,391

WINDSHIELD SCRAPER

Michael J. Dudte, Newton, Kans., assignor to Starkey Developmental Center for Retarded, Inc., Wichita, Kans.

Filed Dec. 23, 1971, Ser. No. 211,825

Term of patent 14 years

Int. Cl. D8—05

U.S. Cl. D7—181

FIG. 1

FIG. 2

FIG. 4

FIG. 3

FIG. 1 is an isometric view of my design for a windshield scraper taken from the upper side thereof;

FIG. 2 is another isometric view of the design taken from the bottom side thereof;

FIG. 3 is an end view of the design taken from the rear end thereof; and

FIG. 4 is an end view of the design taken from the front end thereof.

I claim:

The ornamental design for a windshield scraper, substantially as shown.
